UNITED STATES PATENT OFFICE.

WILLIAM J. MOXLEY, OF CHICAGO, ILLINOIS.

DESIGN FOR A BUTTER OR OLEOMARGARIN BRICK OR PRINT.

SPECIFICATION forming part of Design No. 32,781, dated June 5, 1900.

Application filed May 10, 1900. Serial No. 16,231. Term of patent 14 years.

To all whom it may concern:

Be it known that I, WILLIAM J. MOXLEY, a citizen of the United States, residing at Chicago, Illinois, have invented and produced a new and useful Design for Butter or Oleomargarin Bricks or Prints, of which the following is a specification.

In the drawings, Figure 1 represents a plan view of a butter-print; and Fig. 2 represents a central sectional elevation of the same, taken on line 2.

As shown in the drawings, the leading or important feature of my design consists in a

butter or oleomargarin brick or print having on its upper or top surface a series of parallel ridges or beads A, running diagonally across the surface of the brick, with corresponding channels or depressions a between them.

What I regard as new, and desire to secure by Letters Patent, is—

The design for a butter or oleomargarin brick or print herein shown and described.

WILLIAM J. MOXLEY.
